Des. 208,385
Patented Aug. 22, 1967

208,385

MEAT CHOPPER OR SIMILAR ARTICLE

Naoyuki Iwata and Shigeaki Shinozaki, Nitta-gun, and
Takeshi Tsuruta and Takanobu Fujimoto, Kamakura,
Japan, assignors to Mitsubishi Denki Kabushiki Kaisha,
Tokyo, Japan

Filed Aug. 16, 1966, Ser. No. 3,484

Claims priority, application Japan Feb. 18, 1966

Term of patent 14 years

(Cl. D89—1)

FIG. 1

FIG. 2

FIGURE 1 is a perspective front view of a meat chopper embodying the new design; and

FIGURE 2 is a perspective rear view thereof.

The essential features of our design for a meat chopper are shown in the full line portions thereof on the drawing, the broken line showing of a portion of a ram being for illustrative purposes only.

We claim:

The ornamental design for a meat chopper or similar article, substantially as shown and described.
